[57] CLAIM

The ornamental design for a paper towel holder, as shown and described.

DESCRIPTION

FIG. 1 is a front, right side, and top perspective view of a paper towel holder showing my new design. A roll of paper towel is shown in broken lines and is not part of the design; FIG. 2 is a top plan view thereof; FIG. 3 is a front elevation view thereof; FIG. 4 is a bottom plan view thereof; FIG. 5 is a right side elevation view thereof; FIG. 6 is a left side elevation view thereof; and, FIG. 7 is a rear elevation view thereof.
